UNITED STATES PATENT OFFICE

ARTHUR HILL-TREVOR GLENNY, OF LONDON, ENGLAND

INDEXING OR LIKE APPARATUS

Application filed October 20, 1931, Serial No. 569,996, and in Great Britain October 21, 1930.

This invention comprises improvements in or relating to indexing or like apparatus and is concerned with devices of the kind comprising a base or support for the mounting in different positions of index or like devices comprising rods, pins or pegs on which discs, tabs, labels or similar means are placed for indicating different data or functions whether temporary or permanent.

10 The object of the invention is to provide improvements of constructions which facilitate assembly and removal of the index supports while allowing ease of access to the different parts and ready adjustment, manipulation, changing or removal of the index devices.

According to this invention, indexing or like apparatus comprises a rod or standard, a support or supports for indexing or like devices radiating from said rod or standard, and attachment means such as split collar devices adapted for permitting the support or supports being individually secured to or removed from the rod or standard by lateral approach or withdrawal. Generally a number of the supports would be employed mounted one above another on a standard and as will be seen the split collars provide a ready means by which the supports can be attached to or removed from the rod or standard. The collars are completely detachable from the rod or standard so that if any support is removed, the others may be moved along to fill up the gap. They also allow the supports to be moved readily from one position to another, higher up or lower down, on the standard. It is preferred to arrange for the supports to be swingable about the axis of the rod or standard so that any of them may be displaced laterally from others to facilitate access to it or to the index devices thereon. It is of advantage, however, to mount the several supports on a common sleeve on the rod or standard so that a set of supports can be moved along, or up

and down, as a whole to facilitate inspection or manipulation of the index devices. Counterpoise mechanism may be provided to make this movement easy and, in order that the set of arms shall not move out of position laterally, the rod or standard and the bore of the sleeve may be of square section or some other equivalent means provided such as feather and groove engagement between the sleeve and standard. The counterpoise mechanism may be adapted for adjustment to suit the addition of other index supports to the rod or standard or the taking away of any of the supports. The supports suitably take the form of arms of inverted channel-section bar and the index devices may comprise spring clips adapted to be slipped on to the bars by an upward movement, the clips carrying forwardly projecting rods, pins or pegs for the index tabs or the like.

The support arms may be secured to the collars through the medium of devices which permit adjustment of the arms for securing horizontal positioning of the latter. These devices suitably comprise T-shaped members secured to the arms and adjustably secured to the collars by screws as will be herein-after described.

In order to enable the invention to be readily understood reference will be made to the accompanying drawings illustrating by way of example one practical construction for carrying the invention into effect, in which drawings:—

Figure 1 is a perspective view of an apparatus in accordance with these improvements, portions being omitted as indicated by the broken lines.

Figure 2 is a sectional elevation illustrating the adjustable means for securing the support arms to the standard.

Figure 3 is a plan of Figure 2.

Figure 4 is a front elevation of the counterpoise device shown in Figure 1.

Figure 5 is a section on the line V—V
Figure 4.

Figure 6 is a plan of Figure 4 and Figure 7
is a cross-section through a support *a* and
clip *u*.

Referring to the drawings a number of
the arm-like supports *a* are mounted, one
above another, on a vertical rod or standard
b which is fixed between brackets *c c'* on the
10 floor and ceiling. There also extends be-
tween the brackets *c c'* another rod *d* behind
and parallel to the rod *b* and this serves as a
guide for a counterpoise weight device *e*.
The support arms *a* are mounted on an elon-
15 gated sleeve *f* on the front rod *b* and this
sleeve is connected with the counterpoise
weight *e* by a sprocket chain *g* or the like
passing over a pulley *h* on the upper bracket *c*.
The sleeve *f* with the index arms *a* can thus
20 be moved readily up and down. The rods *b d*
are of square section and the top and bot-
tom of the sleeve *f*, and the counterpoise de-
vice *e* are correspondingly bored or formed
so that turning of the set of arms *a* laterally
25 and lateral displacement of the counterweight
are prevented in the up and down movement.
The support arms *a* suitably comprise in-
verted channel-section bars which are ap-
plied to the sleeve *f* on the rod or standard *b*
30 by means of split hinged collars *i* and T-
pieces *j*. The bars are bolted or riveted at
k to the horizontally disposed stems of the T-
pieces, which are pivotally mounted between
wing pieces *l* on the collars *i* by means of
35 screws or bolts *m* at the junction of the stem
and the cross-bar of the T. The cross bars
of the T-pieces *j* are chamfered or cut away
at *n* to permit pivotal movement of said pieces
on the collars *i*. The collar parts are hinged
40 together at *o* on the side remote from the
wing pieces *l*. The split *p* on the other side
is along the inner face of one of the wings,
preferably the rear one so that a part *q* of the
collar projects rearwardly from the front
45 wing. This part *q* is at right-angles to the
wing and serves as a suitable bearing surface
for a pair of screws *r* which are mounted in
holes in the cross-bar of the T on either side
of the stem and enable horizontality of the
50 bar *a* to be preserved. If the bar happens to
be out of the true, the screwing up of one or
other of the screws *r* enables horizontality
to be regained, by pivoting the T-piece on
the collar. The support arms *a* are spaced
55 apart upon the long sleeve *f* by means of
narrow two-part collars *s*, the halves of which
are tightly clamped together around the
sleeve *f* by screws or bolts. The split collars
i are of such a diameter that they are held
60 sufficiently loosely on the sleeve *f* to enable
the arms *a* to be swung about the axis of the
front rod or standard *b* when desired. These
collars *i* are held closed by the pivot screws
or bolts *m* of the T-pieces. The latter, being
65 disposed between the wings *l* of the collars,

which wings are as deep as the collars and
substantially as long as the cross-bar of the
T-pieces, it is impossible for the channel bars
a to tilt forwardly or backwardly and thus
disalign the index devices, when any support
arm *a* is swung about the front rod or stand-
ard *b*. 70

The index devices comprise rods *t* which
are carried by rectangular clips *u*. The lat-
ter are formed by bending a rectangular piece
of metal to U-form with the sides directed
upwardly and the front one longer than the
rear one. The clip is made about as wide
80 transversely as the thickness of one of the
sides of the inverted channel-bar support
arms *a* and the clips *u* are engaged with the
channel bars by clipping them upwardly on
to the front side of the bars. The short tongue
of a clip engages inside the bar while the long
tongue is outside. The last-mentioned tongue
is preferably made deeper than the bar and
bent over rearwardly at *v* at the top to engage
the top side of the bar to prevent displace-
ment and canting of the clip. The shorter
tongue is also bent over rearwardly at *v'* at
85 the top to facilitate application of the clip
to the bar. The rods *t* are preferably secured
to the clips *u* at the lower part of the latter
and aluminium liners *w* may be inserted in
the bend of the clips to provide a firm founda-
90 tion. The liners *w* also serve as runners when
the clips are slid along the channel bars *a*.
The rods *t* project forwardly from the clips
and may be about five to six inches long.
Upon the rods *t* the index tabs, labels or the
95 like *x* are secured. These may be of disc
form, rectangular or otherwise, of various
colours, and perforated to take over the rods.
It is preferred to make them of thin celluloid
and to split them at *y* from the outer edge
100 to the perforation to enable them to be passed
on to the rods *t* or removed therefrom by
simply springing the split parts over the rods.
They may also be of different sizes, partic-
ularly in the case of number tabs. These lat-
105 ter are suitably of rectangular strip form
with one, two or more perforations to enable
them to be placed at different elevations on
the rods. They may also be of different
lengths. Small clips *z* may also be placed
astride the rods *t* for holding indicating tabs
or labels parallel-wise thereon, and the vari-
ous indicating tabs may be kept apart or
segregated in groups by means of split-rings
110 which fit tightly on the rods. Other labels
x' may be applied to the clips *u*, if desired, by
forming the front jaw thereof with upward-
ly directed spring tongues *2* into which the
labels are slipped. There is an advantage in
mounting the rods *t* at the lower part of the
115 clips *u*, because the labels or tabs *x* hanging
on the rods do not obscure any label or ticket
which may be inserted above the rod in the
spring tongues *2* of the clips.
120 The rods *t* may be bent upwardly and rear-
130

wardly at 3 at the forward ends to prevent injury to the hand or eyes in using the apparatus.

The index devices may relate to persons, objects or other things and by the aid of the apparatus it is possible to provide a reliable visible index or indicator for many different purposes, such as for checking the duties of staff, for analysis of sales and salesmen's results, or for controlling the expenses and progress of working in factories and workshops. Sets or groups of indicating discs α along a rod t may be indicative of the operations in the different weeks of a month or 15 the months of a quarter or year. Other particulars, such as analyses or totals, may be placed on cards α' in the spring tongues 2 on the rod-supporting clips u . It will be seen that all index tabs, discs or cards are 20 readily visible while the index devices as a whole are easily applied to their supporting bars and can be readily adjusted along the bars or removed therefrom. There may be any number on the bars according to requirements. Moreover, any bar a can be swung out horizontally so that any particular set 25 of index devices may be isolated and be readily accessible for individual inspection and one of the bars is shown in this position in 30 Figure 1. It will be seen that the collars i permit the insertion or removal of the arms from the standard b laterally, the remaining arms being capable of adjustment along the rod to fill up or make a gap. A handle 11 35 having a sleeve portion 12 fitted around the sleeve f is provided for vertically adjusting the arms a . On the insertion of a new arm or removal of an arm, the weight of the set as a whole will be altered and to compensate 40 for this the counterpoise weight e may be constructed for attachment or removal of corresponding weights. The counterpoise, see Figures 4, 5 and 6, suitably comprises a rectangular casing 4 with square perforations 5 top and bottom to engage the rear 45 rod or standard d of the apparatus. This casing may be open at the back and have certain weights 6 permanently secured therein to balance the weight of the sleeve f on 50 the front standard b . At the top, within the casing, means are provided for receiving lead strips or other weights 8 each of which is equal in weight to one of the support arms a . For instance there may be a ledge or 55 ledges 9 in the casing with upstanding prongs 7 for receiving the lead strips which would be perforated to take over the prongs. The permanent weights 6 may, of course, be such as to balance a certain number of arms as 60 well as the sleeve f on which they are placed. With this a less number of lead strips would be necessary. Coil springs 10 may be mounted at the top and bottom of the front standard b to serve as abutment springs for the 65 sleeve f and it will be seen that the provision

generally is such that the index devices as a whole may be moved up and down with facility for convenience of access and inspection. Obviously, however, the counterpoise mechanism e is not essential, and in small models particularly, the index arms may be mounted on a short rod or standard mounted in brackets on a wall or upstanding from a table or other support.

It will be observed that all the parts of the apparatus are of relatively simple construction and that the channel bars, sleeves, clips, rods, the indicating discs or tabs and other parts are all capable of production by repetition so that they may be economically manufactured.

I claim:

1. Indexing or like apparatus, comprising a rod or standard, a plurality of horizontal support arms radiating from said standard, mountings adapted for permitting attachment and removal of said arms individually to and from said standard, adjustable devices secured to said arms and pivotal on a horizontal axis in said mountings, and index-carrying rods detachably secured to said arms.

2. Index or like apparatus comprising an upright standard, horizontal arms radiating from and vertically adjustable on said standard, a split collar device secured to each arm and rotatably mounted around said standard and a hinge embodied in said device to permit opening of the device and individual attachment and withdrawal of an arm from the standard.

3. Index or like apparatus comprising an upright standard, a series of split collars rotatably and vertically adjustable on said standard, a vertical hinge embodied in each collar to permit opening of the collar and attachment and detachment from the standard by lateral approach or withdrawal, vertical parallel walls on said collar, a horizontal pivot between said walls, a horizontal arm mounted on said pivot, a screw adapted for adjusting the horizontality of said arm, and index-supporting rods adjustably mounted on said arms.

4. Index or like apparatus comprising an upright standard, a sleeve vertically adjustable on said standard, a series of split collars rotatable on said sleeve, a vertical hinge embodied in each collar to permit attachment and detachment from the sleeve and standard by lateral approach and withdrawal, a vertical pocket formation on said collar, a horizontal pivot in said pocket formation, a trough section arm, a T-shaped extension formed with chamfered surfaces on its head portion on the end of said arm and mounted on said pivot, screws operative on said T-shaped extension for adjusting horizontality of said arm, clips mounted on said trough

section arms, and index-carrying rods extending from said arms.

5. An indexing or like apparatus comprising a pair of upright standards, a sleeve vertically adjustable on one standard, mountings rotatable on said sleeve and adapted to be opened to permit attachment and detachment from the sleeve by lateral approach and withdrawal, horizontal arms supported by said mountings, index-carrying rods, clips for detachably securing said rods to the arms and a counterpoise connected to said sleeve and vertically guided on the other standard.
